UNITED STATES PATENT OFFICE

LOUIS D. GREEN, OF SAN FRANCISCO, CALIFORNIA

SURGICAL INSTRUMENT

Application filed April 30, 1930. Serial No. 448,607.

This invention relates to surgical instruments and is particularly adaptable to instruments having a rotatable tool for performing certain operations on the eye.

5 In devices of this character, it is desirable that the hand of the operator be unimpeded by cords, flexible rotating shafts, or other connections extending from the instrument. Such extensions render the instrument difficult to control and not only do they present an obstacle to a successful operation, but occasionally they are the direct cause of a serious accident, even in the hands of a skilled operator.

10 It is one object of this invention to devise a surgical instrument of this type in which the motive power is contained within the instrument, thereby obviating the necessity of external connections.

15 Another object is to devise a surgical instrument of the character described which is compact and convenient to handle.

20 Still another object is to devise means for easily and quickly controlling the application of power to the rotating parts of an instrument of this character.

25 A further object is to devise an instrument of this type in which a spring is employed as the motive force for rotating the tool and in which convenient means is provided for winding the spring.

30 Other objects will become apparent to those skilled in the art as the detailed description of one embodiment of my invention proceeds.

35 Referring to the drawing:

Fig. 1 is an elevational view partly in section of one form of a surgical instrument embodying the invention.

40 Fig. 2 is a cross section taken on the line 2-2 of Fig. 1.

Fig. 3 is a cross section taken on the line 3-3 of Fig. 1.

45 Fig. 4 is a cross section taken on line 4-4 of Fig. 1.

Fig. 5 is a cross section taken on line 5-5 of Fig. 1.

50 Fig. 6 is a cross section taken on line 6-6 of Fig. 1.

Fig. 7 is a detail view partly in section showing the stop mechanism.

Fig. 8 is an elevation of the device.

Briefly, the embodiment of the invention illustrated in the accompanying drawing comprises a surgical instrument having a pencil-like form. A rotatable tool is mounted on one end of the instrument and this tool is driven by energy stored up in a spring inside the body portion of the instrument. A cap on the other end of the device is utilized for winding the spring and a button 55 on the device controls the starting and stopping of the rotational movement of the tool.

Referring now to the drawing, I have shown an instrument comprising a casing 16, preferably of cylindrical form, within which 60 a spring 17 is disposed. Spring 17 is wound by a turning movement of cap 18 on the end of the instrument and the energy thus stored up is employed to rotate tool 19 at the other 65 end of the instrument.

70 Cap 18 is provided with a milled or knurled periphery and is mounted on a central hub 15 from which a reduced portion extends forming a stud 20 which is journaled in a plate 21 covering the end of casing 16. A stem 22 is secured to stud 20 to rotate therewith.

75 Stem 22 is preferably square in cross section and fits loosely into a square opening in a collar 23 in a manner which prevents relative rotational movement between these parts but 80 which allows movement to a limited extent of collar 23 in a longitudinal direction along stem 22. One face of collar 23 is provided with a plurality of ratchet teeth 24 which are adapted to engage complementary teeth in a 85 stationary collar 26 fixed to plate 27. A compression spring 25 extends between collar 23 and plate 21 for resiliently urging collar 23 against collar 26. For spacing plates 21 and 27 a plurality of spacer rods 28 are provided 90 having reduced end portions which engage suitable openings in the respective plates.

95 Stem 22 passes through collar 23 and is preferably integral with a circular portion 29 journaled in plate 27 and portion 29 has secured thereto an enlarged end portion 31 to which one end of spring 17 is connected. The other end of spring 17 is connected to a shaft 34 which is mounted for rotation relative to member 31 and for this purpose it is provided 100

with a stud 36 which is journaled in a bearing 37 in the end of member 31.

When cap 18 is wound to wind spring 17, collar 23 ratchets over the teeth in collar 26.

5 The teeth on collars 23 and 26 are so shaped that they engage one another to prevent rotation in the opposite direction and in this manner prevent spring 17 from unwinding.

The bottom end of shaft 34 is journaled in 10 plate 39 and fixed to this shaft is a gear 41.

Spacer rods 40 are provided which serve to maintain plates 27 and 39 in spaced relation. Gear 41 meshes with a pinion 42 fixed to a 15 spindle 43 which carries a gear 44. Gear 44

meshes with a pinion 46 on shaft 47 and a gear 48 fixed to shaft 47 meshes with a pinion 49 on shaft 51. A gear 52 mounted on 20 shaft 51 meshes with a pinion 53 which drives shaft 54 and tool 19. Pinion 53 causes rotation of gear 56 which meshes with a pinion 57

and pinion 57 causes rotation of the gear 58 which meshes with pinion 59. A gear 61 on the shaft of pinion 59 meshes with a pinion 62 on shaft 63.

25 Mounted on shaft 63 is a weight 64 adapted to rotate therewith. Weight 64 acts as a fly-wheel and serves to moderate the speed of the rotating parts and tends to keep the speed substantially uniform. A fan 66 is also fixed

30 to shaft 63 which serves as a retarding member to further moderate the speed of the parts. Shaft 63 normally rotates at a relatively high speed. Fan 66 places a load on this shaft and retards it somewhat while weight 64, by its

35 inertia, tends to eliminate possible fluctuations in the velocity of the shaft. By placing a load of this character on the last gear in the gear train and driving tool 19 by an intermediate gear in the train, the speed of

40 tool 19 remains substantially constant under normal conditions. Any departure from constant speed in shaft 63 is greatly minimized in its effect on the rotation of tool 19 on account of the relatively slower velocity of the

45 tool 19.

Spaced plates 67 and 68 having rods 69 extending therebetween serve as convenient supports for journaling various shafts and spindles included in the gear train.

50 A sleeve 71 is fixed to plate 68 and through the opening in this sleeve shaft 54 extends. A collar 72 on shaft 54 and preferably integral therewith abuts against one end of sleeve 71. Extending beyond collar 72 is a screw 73 se-

55 cured to shaft 54 forming a screw connection for tool 19. This type of connection forms a convenient means for replacing tool 19 at will. A tapering portion 76 secured in any suitable manner to casing 16 surrounds sleeve 60 71 and gives the instrument the general appearance of a pencil.

A set screw 77 passing through casing 16 and engaging one of the plates, such as plate 27, serves to secure the entire assembly within 65 the casing. When screw 77 is loosened the

entire assembly may be bodily removed through the top of the instrument.

For starting and stopping the rotation of tool 19 I have shown a pin 81 mounted on one leg of a bifurcated member 82 positioned for convenience between plates 39 and 67. Pin 81 extends through an aperture 83 in plate 67 and engages fan 66. A suitable finger button 84 passing through casing 16, when depressed, causes movement of pin 81 out of the path of fan 66, thereby allowing the train of gears to set tool 19 in motion. A compression spring 86 extending between a stop 87 and a projection 88 on bifurcated member 82 normally urges pin 81 into the path of fan 66. Preferably, button 84 extends through the casing at a point which is near one of the operator's fingers when the instrument is grasped in the manner in which a pencil is held. By positioning button 84 in this location it is apparent that but one hand is required to operate the instrument and that the instrument may be immediately started or stopped without releasing the hold and without moving the instrument. It is to be understood that, instead of fan 66, any one of the other rotating parts of the gear train can be stopped by a suitable projection extending from button 84.

Tool 19 is provided with an annular cutting edge 86 and in order to determine the depth at which this edge is cutting I provide a shoulder 87 on tool 19. Shoulder 87 serves to limit the depth of the cut and by watching the distance between shoulder 87 and the surface the operator can tell at a glance how far the instrument has penetrated.

While I have shown and described a certain embodiment of my invention, I do not wish to be limited thereto, since the invention as defined in the appended claims can be embodied in a plurality of forms.

I claim:

1. In a surgical instrument for performing operations on the human eye, a rotatable tool having an annular cutting edge, a shoulder on said tool for indicating the depth at which the tool is operating, a helical spring for storing energy to rotate said tool, a gear train interconnecting said spring and said tool, said tool being driven by an intermediate gear in said gear train, a rotatable shaft driven by said gear train at a higher rate of speed than said tool, a fan on said shaft for retarding the rate of rotation of said tool, 110 a fly-wheel on said shaft for maintaining the rate of rotation relatively constant, an elongated casing having the general form of a pencil for supporting said tool, said gear train and said spring in general alignment 115 and with said tool extending from one end of the casing, a cap on the opposite end of said casing for winding said spring, a finger button projecting through said casing for controlling the rotation of said tool, said 120

125

130

finger button being disposed at a position which is adjacent the forefinger when the instrument is held between the thumb and forefinger in the manner by which a pencil is held, and a set screw for securing said casing in proper position about the gear train and spring, all of the operating parts of the device including the spring being removable through one end of the casing for inspection

10 upon removal of said set screw.

2. In a surgical instrument, an elongated mounting, a shaft extending from one end of the mounting for connection with a tool, a journal for said shaft carried by the mounting, a helical spring carried by the mounting and alined with respect to the axis of said shaft, gearing carried by the mounting and positioned between one end of the spring and said journal, said gearing serving to connect 15 the spring to said shaft, speed governing means likewise carried by the mounting, a cap disposed adjacent the other end of the mounting, ratcheting means to enable tensioning of the spring by rotation of the cap, 20 a pencil-like casing enclosing the mounting and extending from the cap to said journal, said casing having an end portion in which said journal is socketed, and a release member projecting thru one side wall of the shell 25 to control rotation of the shaft.

3. In a surgical instrument, a rotatable tool, a spring for storing energy to rotate said tool, a gear train interconnecting said spring and tool, means for governing the 30 rate of rotation of said tool, common mounting means for the tool, the spring, and the gear train, an elongated pencil-like casing enclosing the sides of the instrument with the tool extending from one end of the casing, a rotatable cap on the opposite end of the casing for winding the spring, a finger button projecting thru one side of the casing for controlling rotation of the tool, and a member for securing the casing in proper 35 position about said common mounting, whereby upon removal of said member said mounting together with the parts connected thereto, can be removed from the casing.

40 In testimony whereof, I have hereunto set
50 my hand.

LOUIS D. GREEN.
